UNITED STATES PATENT OFFICE.

JOHN WM. PAYLER, OF DETROIT, MICHIGAN.

SLIDE-VALVE.

SPECIFICATION forming part of Letters Patent No. 337,613, dated March 9, 1886.

Application filed July 12, 1884. Serial No. 137,552. (Mod. el.)

To all whom it may concern:

Be it known that I, JOHN WM. PAYLER, of Detroit, county of Wayne, State of Michigan, have invented a new and useful Improvement 5 in Slide-Valves; and I do hereby declare the following to be a full, clear, and exact description of the invention, such as will enable others skilled in the art to which it pertains to make and use it, reference being had to the accompanying drawings, which form a part of this specification.

My invention relates to slide-valves for steam and other cylinders; and it consists of the novel combination of devices and appliances, as hereinafter more fully described, and more particularly pointed out in the claims.

The object of my invention is, first, to afford an improved slide-valve, whereby the admission of steam or other motive force to the cylinder will be cut off earlier and sharper, as required, by the exigencies of the varying load than has hitherto been accomplished by slide-valves in ordinary use; second, to relieve the steam-pressure upon the back of the valve, 25 and, third, to reduce to a minimum the wire-drawing of the steam. I accomplish these objects by constructing a slide-valve having its induction-edges movable by means of suitable mechanism connected and arranged so as to be 30 operated automatically by the governor or independently by the operator, or by both combined.

In the drawings I have illustrated my invention as applied to a horizontal engine, in 35 which Figure 1 is a vertical section showing the steam-chest located above the cylinder. Fig. 2 is an enlarged view of the slide-valve and the ports of the cylinder in cross-section. Fig. 3 shows how the device is operated automatically by the governor. Fig. 4 is an enlarged view in cross-section. Fig. 5 is a plan view of the valve. Fig. 6 is an inverted plan.

I carry out my invention as follows:

A of the drawings indicates the steam-cylinder.

a and *a'* are the steam-ports.

a'' is the exhaust-port.

B is the piston.

C is the steam-chest.

50 D is my improved slide-valve. E is the rod by which the valve is actuated. The valve D is constructed with movable induction-edges

d. These edges may be made movable by any suitable mechanism connected therewith, as shown in the drawings. These edges have 55 extensions *d'*, which run up to the top of the main body of the valve, each being provided with an arm, *d''*, adapted to be engaged by an operating-lever, F, which is pivoted upon the back of the valve by a pin passed through a 60 slot in the lever, whereby the lever is also adapted to move lengthwise.

G is an adjustable tripping-bar arranged to throw the lever F as the valve is reciprocated, by means of which throw in either direction 65 the arms *d'* are alternately forced forward, thereby suddenly projecting the corresponding movable edge *d* in advance of the movement of the valve, and thereby cutting the admission of steam off the cylinder earlier and 70 sharper than would be accomplished by the ordinary movement of the valve deprived of said movable edges. The body of the valve of course is moving in the same direction, and by the time the movable edge is returned to its 75 seat by means of any suitable spring, a stationary stud or other device, H, the port would be suitably closed. The ejection-edges shown at *d''* are fixed and unmovable.

I is the bridge connected with the rod E. 80

J is the valve-case. To relieve the pressure from the back of the valve, the valve-case is provided with plates K, secured thereto, bearing upon the back of the valve. To adjust the position of the tripping-bar G, it may be connected 85 with a hand wheel, a lever, or with the governor-spindle L, as shown in Fig. 3, in order to automatically or independently control the travel of the lever F, and consequently the travel of the movable edges *d*. In this manner 90 said movable edges will be operated to cut off the admission of steam to the cylinder, as required by the exigencies of the varying load.

The plates K, it will be observed, will effectually relieve the pressure of steam upon 95 the back of the valve. Moreover, the position of the tripping device G may be easily and simply regulated, either by hand or automatically, so that the movable edges will be operated to the utmost nicety. This mechanism, 100 it will also be seen, will reduce to a minimum the wire-drawing of the steam, and that too at the very inlet to the cylinder.

The bar G may be made adjustable by means

of a bolt or pin, *g*, inserted through an elongated slot, *g'*, of said bar and secured in the valve-case below. I also prefer to provide the lever *F* with a shoulder or stud, *f*, to engage 5 against the overlapping end of the bar *G*.

What I claim is—

1. The combination, with a slide-valve, of movable edges and the lever *F*, capable of movement lengthwise and adapted to force 10 outward said edges from the body of the valve, substantially as described.

2. The combination, with a slide-valve, of movable edges provided with arms *d'*, and a lever movable lengthwise, adapted to be forced 15 between said arms and crowd said edges outward from the body of the valve, substantially as described.

3. The combination, with a slide-valve, of movable edges, mechanism to throw said edges 20 outward from the body of the valve simultaneously, and springs to retract said edges, substantially as described.

4. The combination, with a slide-valve, of movable edges and a lever movable lengthwise 25 and constructed to force said edges outward from the body of the valve and parallel to each other, substantially as described.

5. The combination, with a slide-valve, of movable edges and a lever capable of endwise 30 motion and constructed to force said edges out permanently from the body of the valve until the pressure of said lever is removed, substantially as described.

6. The combination, with a slide-valve having movable edges, of mechanism for recipro- 35

cating said edges simultaneously and for automatically controlling the travel of said edges, substantially as described.

7. The combination, with a slide-valve having movable edges, of a pivoted lever, *F*, capable of lengthwise and vibratory movement, and adapted to operate said edges both alternately and simultaneously, substantially as described. 40

8. The combination, with a slide-valve having movable edges, and a lever, *F*, capable of 45 operating said edges both simultaneously and alternately, as desired, and plates *K*, adapted to relieve the pressure from the back of said valve, substantially as described.

9. The combination, with a slide-valve having movable edges, of a lever, *F*, capable of operating said edges simultaneously, and an adjustable bar, *G*, to operate said lever, substantially as described. 50

10. The combination, with a slide-valve having movable edges, of a lever, *F*, capable of endwise and vibratory motion, to operate said edges, and an automatically-adjustable bar, *G*, for operating said lever and controlling its stroke, substantially as described. 55

11. The combination, with a sliding valve, of movable edges provided with arms *d'*, and a pivoted lever, *F*, arranged to throw said edges alternately, substantially as described.

In testimony whereof I sign this specification 60 in the presence of two witnesses.

JOHN WM. PAYLER.
